[57] CLAIM

The ornamental design for a paper shredder cutter disc, as shown.

DESCRIPTION

FIG. 1 is a side elevational view of a paper shredder cutter disc showing my new design;

FIG. 2 is a top plan view thereof, the bottom view being a mirror image;

FIG. 3 is a side elevational view thereof, of the opposite side of FIG. 1;

FIG. 4 is another side elevational view thereof;

FIG. 5 is a side elevational view thereof, of the opposite side of FIG. 4; and

FIG. 6 is a sectional view thereof, taken along line 6—6 in FIG. 2.
